UNITED STATES PATENT OFFICE.

RUDOLPH GNICHWITZ, OF ASHBOURNE, ASSIGNOR TO THE MATHER MANUFACTURING COMPANY, OF PHILADELPHIA, PENNSYLVANIA.

DESIGN FOR A FONT OF PRINTING-TYPE.

SPECIFICATION forming part of Design No. 22,412, dated May 9, 1893.

Application filed March 23, 1893. Serial No. 467,378. Term of patent 7 years.

To all whom it may concern:

Be it known that I, RUDOLPH GNICHWITZ, a citizen of the United States, residing at Ashbourne, in the county of Montgomery and State of Pennsylvania, have invented and produced a certain new, useful, and original Design for Printing-Types, of which the following is a full, clear, and exact description.

The essential or leading feature of this design consists in the formation of the characters from angularly arranged or broken straight lines, which feature is specially observable in the curved letters and is measurably observable also in the straight characters in their ragged appearance.

In the drawing illustrating my design, I have shown the upper and lower case letters, a line of figures, a line of punctuation marks, and also the logotypes "Th" and "Co," the

'&,' '\$,' and English pound (money) symbol, 20 all containing in more or less marked degree the aforesaid leading feature of the design.

The broken straight line is specially noticeable in the "C," "e," "O," "o," "3" and "5," and other curved or round characters, and the 25 ragged appearance of the straight letters is specially observable in the "L," "V," "Y," "Z," "j," "m," "v," "w," "y," and "z," and "4" and "7" and exclamation point.

What I claim is—

The design for a font of printing types, substantially as shown and described.

In testimony whereof I have hereunto set my hand this 22d day of March, A. D. 1893.

RUDOLPH GNICHWITZ.
